STRIP OF PRESSURE SENSITIVE LOOSELEAF REINFORCEMENTS

Benjamin E. Smolen, 10 Reed Court, Great Neck, N.Y.,
and George Lerner, 12 Prospect Court, Freeport, N.Y.

Filed Nov. 19, 1959, Ser. No. 58,405

Term of patent 14 years

(Cl. D59—2)

FIG. 1 is a plan view of a strip of pressure sensitive looseleaf reinforcements, showing our new design.

FIG. 2 is a side view thereof.

FIG. 3 is a longitudinal sectional view taken on line 3—3 of FIG. 1.

Our design comprises a series of pressure sensitive looseleaf reinforcements arranged in a row on a backing strip, each reinforcement being generally semi-circular in configuration and having an integral semi-circular tab on the convex side, which tab interfits with the cut-out of the next adjacent reinforcement, all as shown.

We claim:

The ornamental design for a strip of pressure sensitive looseleaf reinforcements, substantially as shown and described.
